UNITED STATES PATENT OFFICE.

RAY S. GEHR, OF CLEVELAND, OHIO.

PLANTER.

1,400,738.

Specification of Letters Patent. Patented Dec. 20, 1921.

Application filed August 2, 1910, Serial No. 575,156. Renewed March 11, 1921. Serial No. 451,480.

To all whom it may concern:

Be it known that I, RAY S. GEHR, a citizen of the United States, residing at Cleveland, in the county of Cuyahoga and State of Ohio, have invented certain new and useful Improvements in Planters, of which the following is a specification, reference being had therein to the accompanying drawings.

This invention relates to seed planters and especially to machines adapted to the planting of corn.

One object of my invention is the provision of an improved form of machine adapted to plant corn in hills with the individual seeds of each hill spaced several inches from each other so that each individual plant is allowed ample opportunity, both below and above ground, for development and growth.

Another object of my invention is the provision, in a machine such as referred to above, of means by which the driver can readily vary the number of seeds deposited in each hill.

Another object of my invention is the provision of a machine adapted to drill the seeds along two parallel lines a few inches apart so as to form a double row that can be cultivated and in other ways treated like a single row.

A further object of my invention is the provision of a machine which is adapted to plant the seeds in hills with the individual seeds spaced apart and which can readily be converted for drilling, either in double rows or in single rows.

The manner in which the various objects are attained and the nature of my improvements will be pointed out in detail in the following description in which, for purposes of illustration, I refer to the accompanying drawings showing a preferred embodiment of the invention.

In the drawings,

Figure 1 is a plan view of the planter, some of the parts being broken away to permit illustration on a large scale.

Fig. 2 is a detail view in vertical section taken on the line 2—2 of Fig. 1.

Fig. 3 is a plan view of one of the seed separating and dropping mechanisms.

Fig. 4 is a vertical section taken on the line 4—4 of Fig. 3.

Fig. 5 is a plan view of a portion of the ring which supports the seed ring.

Fig. 6 is a fragmentary sectional view taken on the line 6—6 of Fig. 3.

Fig. 7 is a similar view taken on the line 7—7 of Fig. 3.

Fig. 8 is an outside elevation of the cut-off and knock-out devices.

Fig. 9 is a plan view of a portion of the seed separating ring.

Fig. 10 is a perspective view of one of the cut-off slides by means of which the number of seeds dropped in a hill may be varied.

Fig. 11 is a plan view of the casting which supports the seed separating mechanism and hopper.

Fig. 12 is a side elevation of the same.

Fig. 13 is a horizontal sectional view taken on the line 13—13 of Fig. 4.

Fig. 14 is a detail plan view of the multiple dropping valve.

Fig. 15 is a vertical section taken on the line 15—15 of Fig. 13.

Fig. 16 is a vertical section taken on the line 16—16 of Fig. 13.

Fig. 17 is a fragmentary sectional view showing a detail of the construction.

It will be seen, on referring to Fig. 1, that my improved planter is similar in general outline to many of the check-row planters now in use. There is a main frame comprising side bars 1, 2, which are united by a cross bar 3, and this frame is mounted upon an axle 4 having ground wheels 5, 5. These wheels, which are of peculiar construction, will be referred to hereinafter.

In front of the main frame is disposed a transverse frame consisting of main bars 6 and 7 which are connected at their ends by check head castings 8, 8 and at intermediate points by cross braces 9 and 10. The transverse frame is pivotally connected to the main frame in the usual manner by pivot pins 11, 11, which pass through the front ends of the frame bars 1 and 2, and lugs or ears formed on the braces 9 and 10, respectively.

12 is a tongue suitably connected to the transverse frame. This frame and the main frame are suitably connected by lever devices, designated as an entirety by 12^a, which are adapted to raise and lower the front frame in the usual manner, *i. e.*, so as to lift the front frame parts free of the ground, and to lower said parts and force the furrow-opening devices, presently to be 110

described, into the ground. It will be understood that a driver's seat is suitably supported upon the main frame. This and other parts are not fully shown for the reason that, as to these features, any preferred construction may be employed.

On the front transverse frame are mounted seed containers or hoppers and separating mechanisms 13, 13, which will presently be described in detail. 14 is a seeder or operating shaft rotatably mounted on the transverse frame and designed to be connected at its respective ends by suitable gearing to the two rotary seed rings. The 10 seeder shaft is driven from the main wheel axle by a chain 15 which passes over any one of a series of various sized sprocket wheels 16 on said axle and over a second sprocket wheel 17 which is rigidly connected to one element of a clutch device 18. By moving the chain 15 from one to another of the sprocket wheels 16, the speed at which the sprocket wheel 17 is driven can be varied. The clutch 18 is of the type having 15 a continuously driven member which turns freely on the seeder shaft, a second member fast on the seeder shaft, and means controlled by the check fork devices for intermittently connecting and disconnecting the 20 two said members to cause an intermittent rotation of the seeder shaft. Clutch devices of this character are well known and in common use, and inasmuch as any one of many forms of these well known devices 25 can be employed in my planter, I have not shown the clutch mechanism in detail. It will suffice to say that the clutch comprises a continuously rotating part 19 which turns freely on the seeder shaft, and an intermittently moving part 20 which is fast on the 30 seeder shaft. The part 20 carries a pawl which tends normally to engage the continuously rotating part to operatively connect it to the intermittently moving part 20. 35 The clutch pawl, however, is normally prevented from engaging the continuously rotating part 19 by an arm 21 which is mounted upon a rocker shaft 22 which carries at its extreme ends the check forks 23, 23. 40 A coil spring 24, which is connected at its front end to a downward extension of the arm 21 and at its rear end to the frame bar 7, serves to rock the shaft 22, and with it, the arm 21 and the check forks 23, forward. 45 The arm 21 is thus normally held in the path of the dogs carried by the intermittently moving part 20 of the clutch and connected to the clutch pawl. When one of these dogs is engaged by the arm 21, it is 50 moved in a way to disengage the pawl from the continuously rotating part 19 of the clutch. When the check forks are engaged and swung backward, the arm 21 is also 55 swung backward out of engagement with the clutch dog, and the clutch is thrown 60 65

into operation. If the clutch is provided with but one dog to be engaged by the arm 21, the seeder shaft will be given a complete revolution at each actuation of the check fork. I prefer, however, to provide two such dogs, for reasons which will presently be explained and by disposing them diametrically opposite each other, the seeder shaft is turned through a half revolution only at each actuation of the check fork.

Referring now to the seed separating devices, it will be observed that the planter shown is of the two-row type, and inasmuch as the seed separating and depositing mechanisms are in all essential respects duplicates of each other, a description of one will suffice. The seed hopper and the seed separating devices at the bottom thereof are supported upon an annular base plate 25. On the inner part of this base plate is rotatably supported an annular bevel gear 26, the base plate 25 being formed with a channel 27 to receive the teeth of said gear. 28 is a bevel pinion on the seeder shaft which meshes with and drives the gear 26. A ring 29 is mounted upon the base plate 25 and on the ring 29 is mounted in turn a seed plate 30 which may be and preferably is in the form of a ring as shown. This seed ring is provided with one or more teeth 31 adapted to be engaged by a lug 26a on the gear 26 so that the seed ring will turn with the gear. The seed ring shown is of the well known edge drop type having seed cells 32 separated by upstanding teeth 33.

The hopper base comprises an outer ring part 34 which rests upon the ring 29, and a crowned bottom wall 35 which is separated at its edges from the ring part 34 by an annular space in which is disposed the upstanding teeth 33 of the seed ring. The hopper base is preferably cast integrally, the two parts 34 and 35 being united by yoke or bridge parts 36.

The ring 29 and the hopper bottom are 110 pivotally mounted on the base 25, the latter being formed with arms 37, 37, in which is mounted a pivot pin 38, and the ring 29 having arms 39, 39, and the hopper base having arms 40, 40, which are mounted on 115 said pin. At its rear side the base 25 carries a swinging bolt 41 with a thumb nut 42 which is adapted to engage a slotted lug 43 formed on the hopper base part 34. By loosening the thumb nut 42 and throwing 120 its bolt out of engagement with the lug 43, the hopper base can be swung forward uncovering the seed plate and gear and their supporting parts, so that the seed plate can readily be removed when it is desired to 125 substitute another. It is sometimes desirable to swing the hopper forward when it contains seed, and to insure the lifting of the seed ring and its supporting ring 29 so as to prevent spilling of the seed, a spring 130

catch 44 is provided which locks the ring 29 to the hopper base (see Fig. 17).

In carrying out my invention, I provide the seed container with a plurality of discharge openings for the seeds, and provide a plurality of ducts to conduct the seeds downward to the ground. The discharge openings, as shown, are disposed at four equidistant points around the periphery of the seed 10 plate, the base casting 25 being formed at these four points with holes or discharge openings 45, 46, 47 and 48, and the ring 29 being formed with four openings which register with the openings of the base casting 25. In the present instance, the ring 29 is formed with an aperture 49 which registers with the hole 45, while the other three openings are in the form of slots, as shown at 15 50 in Fig. 5. The purpose of providing slots rather than apertures at the three discharge 20 openings will presently appear.

Cut-off and knock-out devices are disposed at each of the discharge points. The cut-off device is in the form of a dog 51 pivotally mounted on a pin 52 which is carried by an inclosing casing 53. The free end of the cut-off dog is designed to ride over the upper edges of the seed plate teeth 33 and is pressed yieldingly downward by a spring 54. The knock-out device 55 is pivoted in a similar manner at 56, and is pressed downward at its free end by a spring 57. This knock-out device rides upon the upper edges of the seed ring teeth and drops into each seed cell 35 as the latter passes under it in the usual manner for the purpose of effecting a proper discharge of the seed carried by the cell, it being understood, of course, that the active end of the knock-out is disposed directly 40 over the discharge opening. The knock-out is formed with a stop nose or lug 55^a adapted to engage a lug or projection 53^a on the casing 53 to limit the downward movement of the knock-out. The casing 53 which incloses 45 the cut-off and knock-out devices is open on its outer side, as is shown in Fig. 8, and this open side of the casing is disposed against the upright inner wall of the upper base ring 34, as is shown in Figs. 3 and 6, the 50 said inner wall being made vertical at points adjacent the cut-off and knock-out devices to receive said casing, though it is inclined at intermediate points to facilitate the feeding of the seeds into the cells of the seed ring. The casing 53 is secured in position by a 55 screw bolt 58. The circumferential pitch distance of the cells of the seed ring is a factor of the circumferential distance between the discharge openings and, therefore, as the 60 seed ring is turned, four seed cells pass simultaneously under the four knock-out devices and there is a corresponding simultaneous discharge of four seeds.

In the preferred construction shown the 65 knock-out 55 overlies the cut-off 51 so that

the casings 53 can be made short circumferentially leaving as much space as possible between them in which the cells of the seed ring can fill. As shown in Fig. 3 this latter space is approximately twice the circumferential pitch of the seed ring, so that the time required for each seed cell to pass through said space is approximately that required for the machine to travel twice the distance between hills; and during such passage of the cell through the said space the seed ring is stopped and started twice.

The seeds, when simultaneously discharged, as above stated, pass through the discharge openings in the ring 29 and the 80 base casting 25 into four upright tubular conduits 59, 59, and 60, 60. The base plate 25 rests directly upon the uprights 59 and 60 and is rigidly secured to them by bolts 61, 61, which pass through lugs 62, 62, on 85 the base plate, and lugs 63, 63, on the uprights. The upright conduits are rigidly secured in any suitable manner to the frame bars 6 and 7.

The outside conduits 59, 59, extends downward to a furrow opening runner 64, and at the lower ends of the conduits 60 is disposed a similar runner 65. The lower ends of the conduits are controlled by dropping valves and, in the construction shown, the four 95 valves are formed by a single plate-like ring 66 having four equally spaced slightly elongated openings 67, 67 which are designed to be moved into and out of register with the 90 passages in the uprights 59 and 60.

The valve ring 66 is inclosed in a casing, the upper part 68 of which, as shown in the drawings (see Fig. 15), is cast integrally with the uprights 59 and 60. The lower part 69 of the valve ring casing is cast integrally with the core parts 70 of the two runners 64, and 65, the two parts of the casing being rigidly secured together by bolts 71, 71.

The runners are preferably made as shown, that is, of an inner wrought metal 110 plate 72 which is straight throughout the greater part of its length, and an outer plate 73 of similar material which extends parallel with the inner plate 72 throughout the greater part of its length, but at its front 115 end extends obliquely and merges with the plate 72, the two being preferably welded together. The core or casting 70 of the runner is formed as shown in Fig. 15, being disposed between the plates 72 and 73 and rigidly secured as by rivets 74 to said plates. The core part 70 of the runner is formed with passages 75 and 76, which form continuations of the upright ducts 59 or 60. The forward parts of the runner plates 72 120 are curved upward and at their front ends are bent inward as at 72^a, 72^a, and secured together. A brace 77 extends from the front end of the two runners upward and rearward to the frame bar 6. The object of 125 130

making the inside runner plates 72 straight throughout the active part of their length, is to prevent crowding and packing of the soil between the runners. The runners thus formed are adapted when in working position to make two parallel furrows separated by a ridge that rises to the normal ground level, and in these parallel furrows the seeds are deposited.

10 The dropping valves are actuated by the following means: The valve ring 66 is formed on its inner side with gear teeth 78, and a segmental gear 79 is arranged to mesh with these teeth, the gear 79 being disposed within the valve ring casing which is enlarged, as shown in Figs. 13 and 16, to receive it. The gear 79 is turned by an upright shaft or spindle 80 which carries a bevel pinion 81 at its upper end which 15 meshes with a similar pinion 82 on the check fork rocker shaft 22. A brace bar 83, which is bolted to the frame bars 6 and 7, carries a bearing 84 for the spindle 80, and a bearing 85 for the rocker shaft. The connections 20 are such that when the check fork is swung rearward by its engagement with a tappet on a check wire, the spindle 80 is turned and the segmental gear moved far enough to move the valve 66 from its normal 25 closed position (see Fig. 13) to a position with the valve openings 67, 67, in register each with its corresponding seed duct 59 or 30 60. Then, as the check fork is returned to its normal position by the spring 24, the 35 dropping valves are simultaneously returned to their normal, closed position.

It is clear, from the foregoing description and the construction shown in the drawings, particularly Figs. 13 and 15, that the four 40 seeds discharged from the seed hopper and received upon the dropping valves formed by the ring 66, will upon the actuation of said valves in the manner described, be deposited in the soil, two in each of the two 45 furrows formed by the two runners 64 and 65, and at points equidistant from each other. Preferably, the seeds should be deposited about six inches apart.

Any preferred form of device may be used 50 to cover the seeds, but in the construction shown, I have designed the ground wheels 5, 5, to perform this function. It will be observed that these wheels are of a double 55 construction, the two rim sections being disposed in line with the two furrow opening runners of the adjacent planting mechanism so that each section of the wheel covers the seeds dropped through the runner directly in front of it. In Fig. 1 of the drawings, I 60 have shown the rim of the left wheel in section, and it will be noted that the four hoops or rings 86, 86 and 87, 87 are rigidly connected by suitably shaped cross bars or yokes 88. Shorter transverse bars 89 are 65 rigidly secured to the bars 88, and to the

bars 89 are riveted the spokes 90 of the wheel. The inside hoops or rings 87 are preferably made somewhat wider and also larger in diameter than the outside rings 86, thus throwing the major part of the load 70 upon the inner rings 87 which are more directly connected to the spokes. It will be seen that the two adjacent rings 87 of the wheel form a central ridge part that tracks between the two furrows of the row and tends to crowd the soil outward toward each furrow, while the outside rings 86 form lateral ridge parts that track on the outer sides of the two furrows and tend to crowd the soil inward.

I have set forth in the foregoing description a complete operative mechanism for separating, dropping and covering the seeds, but it may be desirable in soils of varying quality and character to vary the number of seeds dropped in a hill, and it is also desirable to be able to suitably drill the seeds. To accomplish these results, I provide the following devices: The ring 29, which supports the seed ring, has three of its seed discharge openings in the form of slots or notches 50, as previously stated, these slots being disposed above the three discharge openings 46, 47 and 48 of the base casting 25. The hopper base ring 34 also is formed with notches 91 (see Fig. 6) which register with the slots 50. In each of the slots 50 is arranged a flat plate-like slide or valve 92 which rests upon the upper face of the base casting 25, as shown in Fig. 6. The slides 92 are normally in the position indicated in Fig. 6 with the discharge passage through the ring 29 and the base casting 25 open for the passage of seeds discharged from the seed ring. But by moving the slides radially inward, the discharge passage can be closed, and as the width of each slide is equal to the width of the slot 50 in which it is disposed, it will be seen that when the slide is moved inward, the ring 29 is made imperforate, so to speak, so that seeds advanced by the seed ring to the point of discharge will pass smoothly over the slide 92 and the discharge will not be effected. It is 100 desirable in such case to render the knock-out inoperative as otherwise it would strike the seed and possibly crack it. To do this, I form the slide with an upstanding arm or finger 93 which has a beveled end adapted to engage the beveled lower side of the stop nose 55^a of the knock-out so as to raise the latter and hold it in an inoperative position. Of course, if the slide is moved inward when the knock-out is resting upon the upper edge 105 of one of the seed ring teeth, the finger 93 110 will pass freely under the stop nose 55^a.

To render the three slides 92 operable at the will of the driver, each slide is provided with an upstanding lug or pin 94 which co-operates with a cam ring 95 slidably sup-

80

85

90

95

100

105

110

115

120

125

130

ported upon the base casting 25. This ring is formed with cam slots 96, 97 and 98 into which the pins 94 of the three slides extend (see Fig. 3). The three cam slots are 5 substantially equal in length, but it will be observed that the slot 96 has its active or cam part proper at one end, the slot 97 has its cam part half way between its two ends, while the slot 98 has its cam part at one end. 10 The relative arrangement of the three slots is such that if the ring is turned through one step, the slide engaging the slot 96 is closed, while movement of the ring through a second step closes the slide engaged by the 15 slot 97, and final movement through a third step closes the slide engaged by slot 98. It is clear that if one of the slides is closed, only three seeds will be dropped in a hill. If two slides are closed, two seeds will be 20 dropped in a hill, and finally by closing three slides, the mechanism will be adapted for drilling in single rows, it being understood that in such case the check forks are thrown back and secured in inoperative position 25 in the well known manner so that the dropping valves are held open and the seeder shafts caused to rotate continuously. By closing two of the slides and turning the check forks back to inoperative position 30 the machine is adapted to drill the seeds in the two furrows so as to form a double row.

To facilitate the adjustment of the slides 92, the following operating devices are provided. 99 is a bar or link which extends 35 from one seed hopper to the other, and is connected at each end by means of a bolt 100 to one of the cam rings 95. The base plate 25 is formed with a slot 101 through which the said bolt 100 extends. 102 is a 40 foot lever pivoted at its front end on the frame bar 6, and having a pin and slot connection at 103 with the shifting bar 99. The foot lever engages a bracket 104 on the frame bar 7, which bracket is provided 45 with four notches to receive the foot lever and hold it in the four positions corresponding to the four possible positions of the cam rings 95. The numerals 1, 2, 3, 4 are displayed on the bracket 104 above the several 50 notches, and indicate the positions of the foot lever to secure the dropping of one, two, three or four seeds.

I have hereinbefore referred to the desirability of using a partial rotation clutch 55 for transmitting power to the seeder shaft. The advantage of such a clutch is connected with the facts that the possible number of cells in the seed plate is limited and that each cell in the plate cooperates with a 60 plurality of discharge openings in the bottom of the seed container. With a full rotation clutch it would be necessary, when the machine was used for drilling, to have extremely large sprocket wheels on the axle 65 and to drive the seeder shaft at very high

speed in order to effect close drilling of the seeds. The only alternative to such unduly high speed would be the use of seed plates with a very small number of cells for hill planting, but this would be undesirable because it would reduce the period, in relation to the travel of the machine, for each cell to pass through its filling space between the cut-offs. By using the half rotation clutch for the hill planting, the angular speed of the 70 seeder shaft is correspondingly reduced for drilling. 75

The operation of my improved planter will readily be understood from the foregoing description. In hill planting, as the 80 machine moves forward across the field, the active check fork on engaging a wire tappet, is swung backward, and the clutch mechanism is thrown into operation, thus causing a half revolution of the seeder shaft 14. 85 The relation of the gears between the seeder shaft and the seed ring is such that the movement of the seeder shaft causes the seed ring to advance an amount equal to the distance between two adjacent seed cells. This 90 movement of the seed ring carries one of the seed cells past each of the seed discharge openings so that four seeds (assuming that the mechanism is set to drop four seeds in a hill) are simultaneously discharged from 95 the seed ring and pass downward through the upright ducts 59 and 60, and are deposited upon the dropping valves at the lower end of said ducts, said valves having closed just before the discharge of the seeds 100 from the hopper. On the next actuation of the check fork, the four seeds thus deposited on the dropping valves are discharged and dropped at four substantially equidistant points in the furrows made by the two runners, and at the same time, the seed ring is again set in motion to cause the discharge of four more seeds in the manner above described, which seeds, in turn, pass down and are deposited on the dropping valves just 105 after their return to closed position. Thus the cycle of operations is continuously repeated. 110

If at any time the driver wishes to vary the number of seeds dropped, it is only necessary to shift the foot lever 102 and thus close one or more of the slides to render inoperative one or more of the discharge openings. 115

If it is desired to drill the seeds in single 120 rows it is only necessary for the driver to throw the check forks back and secure them in inoperative position, and set the foot lever 102 in the notch marked "1." If the distance apart at which the seeds are then 125 drilled is not suitable, it can be varied by moving the chain 15 to a drive sprocket of different diameter, or by substituting seed plates with a different number of cells, or by making both these changes. 130

To drill in double rows the handling of the machine is the same as for single row drilling except that the foot lever 102 is set in the notch marked "2."

5 In the preferred construction which I have set forth, a separate discharge from the hopper is provided for each of the ducts or passages through which the seeds are conducted individually to the soil. However, it is possible to provide means for distributing the seeds discharged through one discharge opening to two or more ducts or passages leading to the soil, and thus reduce the number of points at which the seeds are 10 discharged from the hopper. A construction of this character is shown in my co-pending application, Serial No. 261,794, filed on the 9th day of November, 1918.

It will be understood that the construction shown and described is merely illustrative of the invention and that various changes in the construction, arrangement and relative dimensions of the parts may be resorted to as conditions may require 25 without departing from the invention as defined in the claims which follow.

What I claim is:—

1. In a seed planter, the combination of a frame, wheels supporting the frame, a container for seeds having a plurality of discharge openings, mechanism for separating individual seeds from the mass in the container and delivering them singly into the respective discharge openings, a plurality of 30 conduits adapted to receive the seeds from the discharge openings and deposit them in spaced relation to each other along two parallel lines, a dropping valve in each of the said conduits, adapted to be actuated intermittently or to be held continuously open, power transmission devices between the said wheels and the said seed separating mechanism adapted to operate either intermittently or continuously, check wire actuated 35 devices for operating the dropping valves and for causing the said power transmission devices to periodically drive the said seed separating mechanism for a period necessary to cause the discharge of one seed 40 into each of the said conduits, and means for rendering all but one of the discharge openings inoperative, whereby, when the dropping valves are held open and the power transmission devices operate continuously, the machine is adapted to drill the seeds one at a time along one of the said parallel lines.

2. In a seed planter, the combination of a frame, wheels supporting the frame, a container for seeds, a plurality of conduits adapted to receive individual seeds discharged from the container and deposit them in the ground along two parallel lines in spaced relation to each other, mechanism 60 for separating individual seeds from the

mass in the container and delivering them singly into the respective conduits, a dropping valve in each of the said conduits adapted to be actuated intermittently or to be held continuously open, power transmission devices between the said wheels and the said seed separating mechanism adapted to operate either intermittently or continuously, check wire devices for operating the dropping valves and for causing the said power transmission devices to periodically drive the said seed separating mechanism for a period necessary to cause the discharge of one seed into each of the said conduits, and means for rendering said seed separating and delivering mechanism inoperative with respect to all but one of the conduits, whereby, when the dropping valves are held open and the power transmission devices operate continuously, the machine is adapted to drill the seeds along one of the said parallel lines.

3. In a seed planter, the combination of a seed container, three or more conduits leading from the seed container downward and adapted to deposit seeds in a definite spaced relation along two parallel lines spaced from each other to form a double row, dropping valves at the lower ends of the conduits adapted either to be actuated intermittently for hill planting or to be maintained inoperative in open position for drilling, means for intermittently operating said valves, means for separating seeds from the mass in the container and discharging one seed at a time into each conduit, means for operating the said seed separating and discharging means either intermittently for hill planting or continuously for drilling, and means for rendering the said discharging means inoperative with respect to all but one conduit on each of the said parallel lines when the seed separating means is operated continuously for drilling.

4. In a seed planter, the combination of a seed container, three or more separate conduits leading downward from said container and adapted to deposit seeds in a definite spaced relation along two parallel lines to form a double row, dropping valves at the lower ends of said conduits adapted either to be actuated intermittently for hill planting or to be maintained inoperative in open position for drilling, means for separating seeds from the mass in the container and discharging one seed at a time into each conduit, means for operating the seed separating and discharging means either intermittently for hill planting or continuously for drilling, means for rendering the said discharging means inoperative with respect to all but one conduit on each of the said parallel lines when the said separating means is operated continuously for drilling, and means for intermittently operating the

dropping valves, the last mentioned operating means being independent of the said separating and discharging means, whereby said valves can be secured in open position 5 for drilling.

5. In a seed planter, the combination of a frame, wheels supporting the frame, a container for seeds having a plurality of discharge openings, mechanism for separating 10 individual seeds from the mass in the container and delivering them singly into the respective discharge openings, a plurality of conduits adapted to receive the seeds from the discharge openings and deposit them in 15 spaced relation to each other along two parallel lines, a dropping valve in each of the said conduits adapted to be actuated intermittently or to be held continuously open, power transmission devices between the said 20 wheels and the said seed separating mechanism adapted to operate either intermittently or continuously, check wire actuated devices for operating the dropping valves and for causing the said power transmission 25 devices to periodically drive the said seed separating mechanism for a period necessary to cause the discharge of one seed into each of the said conduits, and means for rendering inoperative all of the said discharge 30 openings but one on each of the said parallel lines whereby, when the dropping valves are held open and the power transmission devices operate continuously, the machine is adapted to drill the seeds one at 35 a time along each of the said parallel lines so as to form a double row.

6. In a seed planter, the combination of a frame, wheels supporting the frame, a container for seeds, a plurality of conduits 40 adapted to receive individual seeds discharged from the container and deposit them in the ground along two parallel lines in spaced relation to each other, mechanism for separating individual seeds from the mass 45 in the container and delivering them singly into the respective conduits, a dropping valve in each of the said conduits adapted to be actuated intermittently or to be held continuously open, power transmission devices between the said wheels and the said seed separating mechanism adapted to operate either intermittently or continuously, check wire devices for operating the dropping valves and for causing the said power 50 transmission devices to periodically drive the said seed separating mechanism for a period necessary to cause the discharge of one seed into each of the said conduits, and means for rendering the said seed separating and delivering mechanism inoperative 55 with respect to all the conduits except two which deposit their seeds respectively on the separate parallel lines, whereby, when the dropping valves are held open and the power transmission devices operate continu- 60

ously, the machine is adapted to drill the seeds along the said parallel lines.

7. In a seed planter, the combination of means for containing the seeds, means for forming two closely adjacent parallel furrows, separate conduits for receiving seeds from the containing means and depositing them in the respective furrows, and means for separating individual seeds and discharging them from the containing means 70 into the said conduits in such manner that they are deposited one at a time at substantially uniform space intervals suitable for drilling in each of the said furrows to form 75 a double drilled row.

8. In a seed planter, the combination of means for containing the seeds, means for forming two closely adjacent parallel furrows, separate conduits for receiving seeds from the containing means and depositing 80 them in the respective furrows, means for separating individual seeds and discharging them from the containing means into the said conduits in such manner that they are deposited one at a time at substantially uniform space intervals suitable for drilling in each of the furrows to form a double drilled row, and means for varying the rate 85 at which the seeds are deposited in relation to the travel of the machine.

9. In a seed planter, the combination of a seed container, separate conduits arranged to receive seeds from the container and deposit them along two parallel lines spaced from each other so as to form a double row, 100 means comprising a rotary seed plate removably mounted in the container for separating individual seeds from the mass in the container and discharging them into the conduits so that one seed at a time is deposited on each of the parallel lines, mechanism for drying the seed plate at a uniform speed adapted to cause the depositing of the individual seeds at substantially uniform spaced intervals suitable for drilling, 105 and means for varying the speed of rotation of said seed plate.

10. In a seed planter, the combination of a seed container, separate conduits arranged to receive seeds from the container and deposit them along two parallel lines spaced from each other so as to form a double row, means for separating individual seeds from the mass in the container and discharging them into the conduits so that they are deposited one seed at a time on each of said parallel lines at substantially uniform space intervals suitable for drilling at substantially uniformly spaced intervals, and means for varying the rate at which the seeds are 110 deposited on each of the parallel lines in relation to the travel of the machine.

11. In a seed planter, the combination of a seed container, conduits for receiving seeds from the container and depositing them 115

along two parallel lines spaced from each other so as to form a double row, and means for separating individual seeds from the mass in the container and discharging them 5 into the said conduits in such manner that they are deposited one at a time on each of the parallel lines, the said means comprising a seed plate removably mounted in the container and having seed cells that successively 10 move to a point of discharge.

12. In a seed planter, the combination of a seed container, conduits for receiving seeds from the container and depositing them along two parallel lines spaced from 15 each other so as to form a double row, means for separating individual seeds from the mass in the container and discharging them into the said conduits in such manner that they are deposited one at a time on each 20 of the parallel lines, at substantially uniform space intervals suitable for drilling, the said means comprising a seed plate removably mounted in the container and having seed cells that successively move to a 25 point of discharge, and means for varying the rate at which the seeds are deposited in relation to the travel of the machine.

13. In a seed planter, the combination of means for containing the seeds, means for 30 forming two closely adjacent parallel furrows, separate conduits for receiving seeds from the containing means and depositing them in the respective furrows, means for separating individual seeds and discharging 35 them from the containing means into the said conduits in such manner that they are deposited one at a time in each of the said furrows, and means operable at will for rendering inoperative the devices which cause 40 the depositing of seeds in one of the two furrows.

14. In a seed planter, the combination of means for containing the seeds, means for 45 forming two closely adjacent parallel furrows, separate conduits for receiving seeds from the containing means and depositing them in the respective furrows, means for separating individual seeds and discharging 50 them from the containing means into the said conduits in such manner that they are deposited one at a time at substantially uniformly spaced intervals in each of the said furrows, and means operable at will for rendering inoperative the devices which cause 55 the depositing of seeds in one of the two furrows.

15. In a seed planter, the combination of means for containing the seeds, means for 60 forming two closely adjacent parallel furrows, separate conduits for receiving seeds from the containing means and depositing them in the respective furrows, means for separating individual seeds and discharging 65 them from the containing means into the said conduits in such a manner that they are

deposited one at a time in each of the furrows, means for varying the rate at which the seeds are deposited in relation to the travel of the machine, and means operable at will for rendering inoperative the devices 70 which cause depositing of seeds in one of the two furrows.

16. In a seed planter, the combination of a seed container, separate conduits arranged to receive seeds from the container and deposit 75 them along two parallel lines spaced from each other so as to form a double row, means comprising a rotary seed plate removably mounted in the container for separating individual seeds from the mass in the container 80 and discharging them into the conduits so that one seed at a time is deposited on each of the parallel lines, means for varying the speed of rotation of said seed plate, and means operable at will for rendering inoperative the devices which cause the depositing 85 of seeds on one of the parallel lines.

17. In a seed planter, the combination of a seed container, separate conduits arranged to receive seeds from the container and deposit 90 them along two parallel lines spaced from each other so as to form a double row, means for separating individual seeds from the mass in the container and discharging them into the conduits so that one seed at a 95 time is deposited on each of the parallel lines, means for varying the rate at which the seeds are deposited on each of the parallel lines in relation to the travel of the machine, and means operable at will for rendering inoperative the devices which cause the depositing 100 of seeds on one of the parallel lines.

18. In a seed planter, the combination of a seed container, separate conduits arranged to receive seeds from the container and deposit 105 them along two parallel lines spaced from each other so as to form a double row, means for separating individual seeds from the mass in the container and discharging them into the conduits so that they are deposited 110 on each of said parallel lines at substantially uniformly spaced intervals, means for varying the rate at which the seeds are deposited on each of the parallel lines in relation to the travel of the machine, and means operable at 115 will for rendering inoperative the devices which cause the depositing of seeds on one of the parallel lines.

19. In a seed planter, the combination of a container for the seeds, seed separating mechanism comprising a plate formed with seed cells, a plurality of openings for the discharge of seeds from cells of the seed plate, cut-off and knock-out devices arranged at each of said discharge openings, and means 120 controllable at will for closing one or more of the discharge openings and for rendering its or their knock-out devices inoperative.

20. In a seed planter, the combination of a container for the seeds, seed separating mech- 125

anism comprising a plate having seed cells, the container having a plurality of openings for the discharge of seeds from the cells of the seed plate, a device in connection with 5 each of two or more of the discharge openings for closing same, and a common operating means for said devices adapted to actuate them successively.

21. In a seed planter, the combination of a 10 container for the seeds, seed separating mechanism comprising a plate having seed cells, the container having a plurality of openings for the discharge of seeds from the cells of the seed plate, a device in connection with 15 each of two or more of the discharge openings for closing same, a circular plate operatively connected to each of said devices, and means for actuating said circular plate.

22. In a seed planter, the combination of a 20 seed container, a plurality of conduits for receiving the seeds from the container and depositing them in spaced relation in the ground, means for separating individual seeds from the mass in the container and dis- 25 charging them into the conduits, devices adapted to be operated by a check wire for controlling the operation of the seed separat-

ing means, a dropping valve plate mounted at the lower ends of the conduits to turn about an upright axis, and driving connec- 30 tions comprising an upright shaft operatively connected at its lower end to the valve plate and at its upper end to the check wire operated devices.

23. In a planter, the combination of seed 35 separating mechanism, devices for dropping the separated seeds in a hill comprising a plurality of conduits for conducting the seeds of each hill to the ground, and a pair of fur- 40 row opening runners at the lower ends of said conduits, said runners being arranged side by side and spaced from each other and having their front parts laterally controlled and the soil engaging parts of their adjacent 45 sides parallel to each other, whereby clogging of the soil between the runners is avoided.

In testimony whereof I affix my signature, in the presence of two witnesses.

RAY S. GEHR.

N. CURTIS LAMMONT,
A. G. RUSSELL.

Corrections in Letters Patent No. 1,400,738.

It is hereby certified that in Letters Patent No. 1,400,738, granted December 20, 1921, upon the application of Ray S. Gehr, of Cleveland, Ohio, for an improvement in "Planters," errors appear in the printed specification requiring correction as follows: Page 3, line 90, for the word "extends" read *extend*; page 9, line 43, claim 23, for the word "controlled" read *contracted*; and that the said Letters Patent should be read with these corrections therein that the same may conform to the record of the case in the Patent Office.

Signed and sealed this 31st day of January, A. D., 1922.

[SEAL.]

WM. A. KINNAN,

Acting Commissioner of Patents.
